UNITED STATES PATENT OFFICE.

JAMES M. JOHNSON, OF MOBILE, ALABAMA.

COAL-PUSHING DEVICE.

1,411,105.

Specification of Letters Patent. Patented Mar. 28, 1922.

Application filed April 25, 1921. Serial No. 464,344.

To all whom it may concern:

Be it known that I, JAMES M. JOHNSON, a citizen of the United States, residing at Mobile, in the county of Mobile and State of Alabama, have invented certain new and useful Improvements in Coal-Pushing Devices, of which the following is a specification.

The present invention relates to a new and improved coal pushing or feeding device adapted to be used on locomotive tenders or coal cars, or in connection with other means and devices adapted to contain coal in bulk.

The principal object of my invention is to provide a coal pushing or feeding device primarily designed for use in connection with locomotive tenders which is adapted to push or feed the coal toward the normally open end of the tender thus facilitating the "firing" of the engine, or locomotive.

Another object of the invention is to provide a device of the above character which includes means normally positioned behind the bulk of coal together with means and mechanism to move the same longitudinally whereby the coal within the tender may be moved toward the forward end thereof so that the fireman may have access thereto at all times.

Still another object of the invention is to provide, in conjunction with the means above referred to, other means adapted to normally assume a horizontal position and receive part of the bulk of coal carried by the tender, together with automatic mechanism to tilt said additional means at certain times whereby the bulk of coal carried thereby will be fed into the main container portion of the tender.

A further object of the invention is to provide suitable antifriction means to facilitate the operation of the moving parts of the device and the tilting of certain parts thereof as will be hereinafter fully described.

A still further object of the invention is to provide a device of the above character which is of such construction whereby it can be used in connection with locomotive tenders of conventional construction and where- 50 in its application thereto will not necessitate the changing of the normal construction to any appreciable extent.

A still further object of the invention is to provide a device of the above character 55 that is simple in construction, strong and

durable, and which it is believed may be manufactured at a reasonably low cost.

Still another object of the invention is to provide a coal pusher or feeding device which may be controlled from the cab of 60 the locomotive.

Various other objects and advantages of my invention will become apparent during the continuance of the following description.

In the drawings:—

Figure 1 is a view in top plan showing my invention as in its preferred embodiment.

Figure 2 is a view in side elevation.

Figure 3 is a view in longitudinal cross section taken on line 3—3 of Figure 1, the 70 pushing device being shown in full line in its normal position and in dotted lines in an extended position.

Figure 4 is a view in transverse cross section taken on line 4—4 of Figure 1.

In describing my invention in detail 10 designates in its entirety, a conventional form of locomotive tender which is provided with the usual water compartments 11 and 12 to which access may be had 80 through an intake opening 13 that is normally closed by a cover 14, and the main coal containing space 15. Adjacent the forward end of the tender, the sides formed by the water compartment 12 carry a cross 85 piece 16 from which depends the conventional gate 17 that has an opening 18 located in the lower end thereof through which coal may be shovelled. The longitudinal edges of the tender are extended 90 above the upper end of the water compartment 12 as at 19 so as to form an additional space for receiving coal and slightly in advance of the intake opening 13, the water compartment 11 carries an upstanding 95 cross member 20 which serves to mark the rear end of the coal containing space. It will be noted that when the tender is filled with coal the bulk of coal not only occupies the main space or compartment 15 but also 100 lies on the upper end of the water compartments 12 and the upper surface of the water compartment 11 in advance of the cross member 20.

In equipping the tender with the device 105 of my invention, I first provide a steam cylinder 21 which is arranged in the plane of the central longitudinal axis of the tender and so as to project partly within the water chamber 11 as clearly shown in Fig. 110

ure 3. The upper part of the steam cylinder 21 projects above the top of the water compartment 11 as will be noted upon reference to Figure 1, but the main part thereof lies within the water compartment. The steam cylinder carries a piston 22 having a head 23 for operative movement therein and the piston projects through an opening 24 into the main coal compartment 15 as also shown in Figure 3.

Within the water compartment 11 are arranged longitudinal sleeves 25 and 26 through which extend steam pipes 27 and 28 which connect to opposite ends of the steam cylinder 21 as clearly shown in Figure 3. The steam pipes 27 and 28 extend downwardly on the outside of the water compartment and are carried on the under side of the tender by means of brackets 29. The steam pipes are also connected to other steam pipes 30 and 31 that are carried by the locomotive and which are provided with suitable valves (not shown) whereby ingress of steam into the cylinder 21 may be controlled.

On its outer end and within the main coal compartment 15, the piston 22 carries the main pushing member 32 which is of slightly less width than the main coal containing space 15 and which carries at its lower end a gate 33 that is hinged thereto as at 34 for folding movement in one direction. In other words during the forward movement of member 32, the gate will be firmly held in alignment therewith but upon return movement, the gate will fold forwardly upon contact with any loose coal or foreign matter in the bottom of the coal containing space 15. The front face of the member 32 may also be provided with reinforcing members 35 which are secured in place as at 36 and which may be arranged in angular relation with respect to each other as shown in Figure 4. The preferred position of the reinforcing members is in substantially inverted U shape relation, the upper ends thereof coming together at a point preferably in alignment with the piston 22 and the lower ends thereof terminating adjacent the outer, lower edge of the member 32.

At its upper end the member 32 is provided with a series of spaced sleeves 37 through which is arranged a pintle 38 which carries rollers 39 on its outer ends for engagement with tracks 40 carried on the inner faces of the water compartment 12 as clearly shown in Figures 1 and 4. In addition to aiding in the support of the member 32, the pintle 38 and the rollers carried thereby together with the track 40, serve to facilitate movement of the member 32 and prevent sagging thereof.

On that portion on the top of the water compartment 11 in advance of the cross

member 20, I arrange a supplemental pushing or carrying member 41 whose top edge is provided with a depending extension 42 that enters the main coal space 15 and which is in turn provided with spaced sleeves 43 which receive the pintle 38, above referred to, and serve to maintain the supplemental pushing or carrying member 41 in hinged relation to the member 32.

At its rear end the supplemental member 41 is turned upwardly as at 44 and then outwardly as at 45 to project over the cross member 20 when the device is in its normal position and as clearly shown in Figure 3. The sides of the supplemental member are turned upwardly as at 46 and then outwardly as at 47 to project over the upstanding portions 19 of the tender and again bent downwardly to terminate in longitudinal sleeves 48. Between the portion 47 of the supplemental member 41 and the upper edges of the extended portions 19 of the tender are arranged anti-friction rollers 49 which facilitate movement of the supplemental member along the upper edge of the extended portion 19 and serve to eliminate friction therebetween.

In order to compensate for the usually irregular surface of the upper part or top of the water containers, I provide longitudinal spacing members 50 and 51 on which the supplemental member 41 rests and slides during operation.

With a view to providing means to automatically tilt the supplemental member 41 after the same has been moved forward a certain distance, I provide the longitudinal sleeves 48 thereof with longitudinally disposed rods 52 which carry at their forward ends downwardly and forwardly extending trip arms 53 as clearly shown in Figures 2 and 3. At suitable points on the sides of the tender 10 are arranged stop rollers 54 with which the trip arms 53 become engaged after the supplemental member 41 has been moved forward a certain distance. When the trip arms engage the stop rollers 54 and the member 32 continues to carry the supplemental member forward, the angular disposition of the trip arms causes the supplemental member to be tilted until it finally reaches the position shown in dotted lines in Figure 3. It will be observed that the coal contained on the supplemental member will be dumped into the main coal compartment 15 so that the entire bulk of coal carried by the tender will have been placed before the opening 18 in the outlet gate 17.

On reference to Figure 1 it will be noted that the intermediate portion of the supplemental member 41 is suitably curved as at 55 to conform to the contour of the upper part of the steam cylinder 21.

In operation the coal is deposited in the main receiving space 15 and upon the sup-

plemental member 41 in the conventional way. As the fireman shovels the coal away from the opening 18, he may manipulate suitable valves in the locomotive cab so as 5 to cause steam to be admitted to the rear end of the steam cylinder 21 which will force the piston 22 forwardly and carry with it the main pushing member 32 and the supplemental member 41. During the 10 first few feet of movement of the piston, the main pushing force will be exerted by the member 32 and the supplemental member will be carried forward in a horizontal position. However, continued forward 15 movement will bring the trip arms into engagement with the stop rollers 54 so as to tilt the supplemental member 41 in the position shown in dotted line in Figure 3. Thus it will be observed that the entire bulk of 20 coal may be positioned immediately adjacent the opening 18 in the gate 17 from which point it may be easily and quickly removed by the fireman.

From the foregoing it is believed that the 25 advantages and novel features of my invention will be readily understood and therefore further detailed description is deemed unnecessary.

What is claimed is:—

30 1. In a device of the character described, the combination with a locomotive tender or coal car having a coal receiving compartment and said compartment having an outlet opening at one end, of coal pushing means 35 mounted for longitudinal movement within said compartment, a supplemental member carried by said coal pushing means and normally assuming a horizontal position on the top of said tender or coal car, means to 40 move said coal pushing means forwardly and backwardly within said compartment and means to automatically tilt said supplemental member forwardly at a predetermined time during the forward movement 45 of said coal pushing means substantially described.

2. In a coal pushing device for locomotive tenders and coal cars, a main pushing member mounted for longitudinal movement in 50 the main coal compartment of said tender or coal car, means to move said pushing member forwardly and rearwardly within said compartment, and a suitable coal receiving member carried by said main pushing member adapted to be tilted at a predetermined time during the forward movement of said main pushing member, substantially described.

3. The combination with a locomotive 60 tender or coal car having a coal receiving compartment provided with an outlet opening at one end thereof, of a steam cylinder mounted longitudinally behind said coal re-

ceiving compartment, a piston operating within said cylinder and projecting through 65 said compartment, a main pushing member carried by said piston for forward and backward movement within said compartment, a gate carried at the lower end of said pushing member and mounted for foldable relation in one direction with respect to the main piston member, a coal receiving member hingedly mounted on said main pushing member and adapted to normally assume a horizontal position, automatic means including trip arms carried by said coal receiving member and stop rollers carried by said tender or coal car adapted to tilt said coal receiving member at a predetermined time 70 during the forward movement of said main pushing member, means to support said main pushing member during its forward and backward movement independent of said piston, and anti-friction means carried by said coal receiving member engageable with 75 said tender or coal car substantially described.

4. A device of the character specified comprising the combination with a locomotive tender having a coal pit with an outlet opening, of vertically disposed coal-pushing 90 means mounted for reciprocal movement within said pit, a supplemental coal-carrying member hingedly connected to said pushing means adjacent the upper edge and normally lying in a horizontal plane, said member having guide extensions engageable over the side edges of the tender, means for reciprocating the said coal-pushing means and means for automatically tilting the supplemental member at a predetermined point 95 100 in its forward travel.

5. A device of the character described comprising a tender having a water compartment and a main coal space, extension means providing an additional space above 105 the water compartment for receiving coal, a reciprocal coal-pushing member within the main coal space, a cylinder arranged partly within the water compartment and partly within the additional coal space, a piston operable in said cylinder and connected to said coal-pushing means for reciprocating the latter, and a supplemental carrying member filling the said additional coal space and having a curved portion receiving the upper 110 part of the said cylinder whereby the latter serves as a guide for the supplemental member, said member being hinged to the pushing member for movement therewith and means for tilting the supplemental member 115 120 to a discharging position at a predetermined point in its forward travel.

In testimony whereof I affix my signature.

JAMES M. JOHNSON.
